UNITED STATES PATENT OFFICE.

WILLIAM J. HALLOCK, OF JERSEY CITY, NEW JERSEY.

SUBMARINE BOMB.

1,163,146.

Specification of Letters Patent.

Patented Dec. 7, 1915.

Application filed June 25, 1915. Serial No. 36,163.

To all whom it may concern:

Be it known that I, WILLIAM J. HALLOCK, a citizen of the United States, residing at Jersey City, in the county of Hudson and State of New Jersey, have invented a certain new and useful Improvement in Submarine Bombs, of which the following is a specification.

Aviators flying over the sea at considerable heights are able to observe clearly submarine vessels submerged beneath them, and to determine approximately the depth at which such vessels are submerged.

The object of this invention is to provide a bomb which may be dropped from a flying machine or other airship, upon the surface of the water above such vessel or in the path of its movement, adapted to sink in the water and be exploded therein at a depth determined by the aviator to be the same as that of the submarine, so as to cause such explosion to take place as closely as possible to such vessel and thus destroy or disable the latter.

The bomb carries a free light cable terminating in a parachute or other device adapted to support the cable vertically during the descent of the bomb, and the cable is provided with means which upon reaching the surface of the water is acted upon by the latter and the submerged bomb exploded through coacting devices.

The accompanying drawings form a part of this specification and show a preferred form of the invention.

Figure 1 is an elevation on a small scale, showing the bomb in its descent with the cable supported by a parachute. Fig. 2 is an elevation of the bomb alone, on a much larger scale, with a portion at the upper end broken away to show an inclosed battery. Fig. 3 is a vertical section, partly in elevation, showing a mechanical contact device carried by the cable and adapted to be actuated by impact upon the water surface to close the electric circuit. Fig. 4 is an elevation of one of a series of cells carried by the cable and adapted to close the circuit by the action of water on a material serving to hold the inclosed contact-points separated. Fig. 5 is a vertical section of the same, taken on the line 5—5 in Fig. 4. Fig. 6 is a corresponding transverse section taken on the line 6—6 in Fig. 4. Fig. 7 is an elevation corresponding to Fig. 4 but with certain portions removed to show the contact-

points. Fig. 8 is a similar elevation showing the cell in condition to be acted upon by the water.

Similar letters of reference indicate the same parts in all the figures.

A is the bomb, preferably of slender cylindrical form, pointed at the head or lower end to facilitate its entrance into the water and cone-shaped at the rear or upper end to permit the water to close thereover without drag; the form being designed to insure a rapid descent through the water in a vertical path when dropped from a great height.

The bomb has a chamber at A¹ for the charge of high explosive, provided with an electric detonator or exploding device of any approved type, indicated at A², and a battery chamber A³ at the upper end in which is the electric battery A⁴ of any suitable construction for supplying the current required to actuate the detonator.

Wires A⁵ A⁶ project through a plug A⁷ of insulating material at the upper end of the bomb and are provided with means for attaching the corresponding wires B¹ B² of a light cable B thus secured to the bomb. At the free end of the cable is a small parachute C intended by its resistance in falling to straighten the cable during the descent of the bomb and cause the latter to assume a vertical position at or before entering the water and during its descent therein.

Immediately below the parachute is a device, shown in Fig. 3, adapted to collapse by impact against the water surface and complete the electric circuit to actuate the detonator A². As shown it comprises a dished disk D of aluminum or other light material having a flexible diaphragm D¹ covering the lower concave face; the disk D carries an insulated contact-ring D² and the diaphragm carries a similar ring D³, the latter held separated from the former by a light helical spring D⁴ which distends the diaphragm. The rings are suitably connected each to one of the cable wires B¹ B².

The descent of the bomb through the water causes the diaphragm D¹ to strike the surface of the water with sufficient force to overcome the resistance offered by the spring D⁴ and drive the rings D² D³ into momentary contact and thus explode the submerged bomb at a distance beneath the surface determined by the length of the cable. By selecting a bomb equipped with a cable

of the desired length, the aviator may cause the explosion to take place at the desired depth.

In addition to the above described device operated by impact, the cable is provided at intervals with cells F secured thereon, each having a water tight cover F¹ and inclosed spring contact points F² F³ connected to the cable wires and held separated by an insulating layer or pellet, indicated at F⁴, adapted to be quickly dissolved or disintegrated by the action of water and permit the points F² F³ to come together and thus close the circuit. Any material having the soluble properties of starch or calcium carbide combined with the required non-conducting quality may be employed to separate the contact-points. To avoid accidental displacement of the pellet F⁴ in handling with a cover F¹ removed, the points F² F³ are protected by a separable cap or shell F⁵ perforated on its face to admit water readily. With the cable thus equipped the aviator removes the cover F¹ from a cell located at a distance from the bomb corresponding to the estimated depth of the submarine to be attacked and releases the bomb and its attached cable over the vessel if at rest, or if in motion, in the path of the vessel at a point at which it is estimated the latter will arrive at the same time the opened cell reaches the water and causes the submerged bomb to explode.

The impact device may be used without the series of cells or may be omitted and the cells employed alone. The impact device may be made light enough to serve the function of a parachute in maintaining the cable during the descent of the bomb, or if the cable be exceedingly light and thin it may serve successfully alone without the parachute or other sustaining means.

Other modifications may be made in the forms of the parts, and the construction of the impact device and cells may be varied within wide limits without departing from the principle of the invention.

I claim:—

1. A bomb adapted to be dropped from the air into water, an exploding device in said bomb, trailing means attached to said bomb to fall freely therewith and to be maintained vertically during the descent of the bomb through the air and through the water, and collapsible means on said trailing means operable by contact with the water surface to actuate said exploding device.

2. A bomb adapted to be dropped from the air into water, an exploding device in said bomb, trailing means attached to said bomb to fall freely therewith and to be maintained vertically during the descent of the bomb through the air and through the water, collapsible means on said trailing means operable by contact with the water

surface to actuate said exploding device, and means for insuring vertical maintenance of the trailing means during the descent thereof and of the bomb.

3. A bomb adapted to be dropped from the air into water, an exploding device in said bomb, a cable attached to said bomb to fall freely therewith, and means located at intervals on said cable for actuating said exploding device by the contact of a selected one of such means with the water surface during the descent of said bomb in the water.

4. A bomb adapted to be dropped from the air into water, an exploding device in said bomb, a cable attached to said bomb to fall freely therewith, and collapsible means on said cable constructed to be operated by impact upon the water surface and actuate said exploding device during the descent of said bomb in the water.

5. A bomb adapted to be dropped from the air into water, an exploding device in said bomb, a cable attached to said bomb to fall freely therewith and be maintained vertically, and spaced cells located on said cable and adapted to be conditioned for actuating said exploding device by the contact of such cell with the water surface during the descent of said bomb in the water.

6. A bomb adapted to be dropped from the air into water, an exploding device in said bomb, a cable attached to said bomb to fall freely therewith, a series of water-tight cells located at measured intervals on said cable, each of said cells adapted to be conditioned to permit the ingress of water thereto, and when thus conditioned to actuate said exploding device by contact of such cell with the water surface during the descent of said bomb in the water.

7. A bomb adapted to be dropped from the air into water, an electrically operated exploding device in said bomb, a cable attached to said bomb to fall freely therewith, collapsible means on said cable and contact-points carried by such means and adapted to contact by the impact of such means upon the water surface and actuate said exploding device during the descent of said bomb in the water.

8. A bomb adapted to be dropped from the air into water, an electrically operated exploding device in said bomb, a cable attached to said bomb to fall freely therewith, a series of water-tight cells on said cable, contact-points in each cell held separated by material soluble in water, and a removable cover for each of said cells.

9. A bomb adapted to be dropped from the air into water, an electrically operated exploding device in said bomb, a cable attached to said bomb to fall freely therewith and be maintained vertically, electric contact devices on said cable actuated by the action of water thereon, comprising select-

able means carried by the cable for actuating the exploding device at a predetermined distance beneath the surface of the water, and means for maintaining said cable in vertical position during the descent of said bomb and cable.

10. A bomb adapted to be dropped vertically from the air into water, an electrically operated exploding device in said bomb, a cable attached to said bomb to fall freely therewith and be maintained vertically, electric contact devices on said cable and collapsible and operated by impact upon the water, and a parachute on the free end of said cable for maintaining the latter in vertical position during the descent of said bomb and cable.

15. A bomb adapted to be dropped vertically from the air into water, an electrically operated exploding device in said bomb, a cable attached to said bomb to fall freely

therewith and be maintained vertically, electric contact devices on said cable and collapsible and operated by impact upon the water, and a parachute on the free end of said cable for maintaining the latter in vertical position during the descent of said bomb and cable through the air and water.

11. A bomb adapted to be dropped vertically from the air into water, an electrically operated exploding device in said bomb, a cable attached to said bomb to fall freely

therewith and be maintained vertically, electric contact devices on said cable and collapsible and operated by impact upon the water, and a parachute on the free end of said cable for maintaining the latter in vertical position during the descent of said bomb and cable through the air and water.

20. A bomb adapted to be dropped vertically from the air into water, an electrically operated exploding device in said bomb, a cable attached to said bomb to fall freely

therewith and be maintained vertically, electric contact devices on said cable and collapsible and operated by impact upon the water, and a parachute on the free end of said cable for maintaining the latter in vertical position during the descent of said bomb and cable through the air and water.

25. A bomb adapted to be dropped vertically from the air into water, an electrically operated exploding device in said bomb, a cable attached to said bomb to fall freely

therewith and be maintained vertically, electric contact devices on said cable and collapsible and operated by impact upon the water, and a parachute on the free end of said cable for maintaining the latter in vertical position during the descent of said bomb and cable through the air and water.

30. 12. A bomb adapted to be dropped from

the air into water, an electrically operated exploding device in said bomb, a cable attached to said bomb to fall freely therewith, electric contact devices on said cable operated by dissolving a separating insulating medium located between the points of said contact devices by contact with the water, and a parachute on the free end of said cable for maintaining the latter in vertical position during the descent of said bomb and cable.

13. A bomb adapted to be dropped from the air into water, an electric exploding device in said bomb, trailing means attached to said bomb to fall freely therewith, means on said trailing means for maintaining the latter vertically during the descent of the bomb through the air and through the water, electric contact points on said trailing means

operable by contact with the water surface to actuate said exploding device, a perforated cap inclosing said points and constructed to permit access of water thereto, and a removable cover inclosing said cap and supported independently thereof and constructed to exclude water from said points.

In testimony that I claim the invention above set forth I affix my signature.

WILLIAM J. HALLOCK.
